UNITED STATES PATENT OFFICE.

EUGEN BARON RITTER AND CARL KELLNER, OF PODGORA, AUSTRIA-HUNGARY.

APPARATUS FOR THE MANUFACTURE OF CELLULOSE OR PAPER-PULP FROM WOODY FIBER.

SPECIFICATION forming part of Letters Patent No. 329,214, dated October 27, 1885.

Application filed September 13, 1884. Serial No. 143,405. (No model.) Patented in Austria-Hungary August 2, 1883, No. 20,024 and No. 31,730; in France September 27, 1883, No. 157,754; in Belgium September 29, 1883, No. 62,746, and in Italy January 22, 1884, No. 16,316.

To all whom it may concern:

Be it known that we, EUGEN BARON RITTER and CARL KELLNER, subjects of the Emperor of Austria-Hungary, and residents of Podgora, in the Empire of Austria-Hungary, have invented certain new and useful Improvements 5 in Manufacturing Paper-Pulp, of which the following is a specification.

This invention has relation to an apparatus 10 for the manufacture of cellulose or paper-pulp from woody fiber by the action of sulphurous-acid solution or other similar or equivalent substance upon the fiber.

The invention which forms the subject-matter 15 of the present application is adapted to the carrying out of a certain novel process which we propose to make the subject-matter of another application.

Our present invention, having in view the 20 carrying out of the process referred to, therefore consists in the novel construction, combination, and arrangement of parts herein-after described and specifically claimed.

Referring to the accompanying drawings, 25 Figure 1 is a vertical sectional view of our improved apparatus, and Fig. 2 a plan view of the same.

A B designate two boilers or digesters of the 30 ordinary or any suitable size or construction, and should be lined with lead or other acid-resisting substance, to prevent the deleterious action of the digesting-solution upon their exterior casing, which is ordinarily of iron.

C designates a tank which contains the fresh 35 solution by means of which the fiber is to be disintegrated; C', a tank adapted to contain fresh water. A pipe, 1, leads from the tanks C and C' over the tops of the boilers, and branches 2 and 3 lead from the pipe 1 to and 40 open into the boilers or digesters A B at a point in their sides slightly above gratings a b, which are fixed in the boilers to prevent the wood from rising above the liquid contents of the boiler. The pipes 2 and 3 are provided 45 with cocks 6 and 5, by means of which the flow of liquid may be regulated, and when desired entirely cut off. Alongside of and slightly below the pipe 1 is arranged a pipe, 4, which has a communication with a steam-generator

and a generator of sulphurous acid. (Not 50 shown.) The pipe 4, after passing over the boilers A B, turns down and terminates at c, where it enters a conduit, c'. The pipe 4 has two branches, 7 and 8, which pass down alongside of the boilers A B and enter at the bottom 55 of the same, where they are provided with stop-cocks 9 10. In addition to the pipes 7 and 8, the pipe 4 has two other branch pipes, 11 12, which enter the boilers A B at the top thereof, and are provided with stop-cocks 13 60 14. The pipe 4 has also two stop-cocks, 15 16, whose purposes will be explained hereinafter. The boilers A and B are provided with waste-pipes 17 18, through which the liquid contents 65 of the boiler are allowed to run off after having been used.

Operation: In describing the operation of the above apparatus it will be presumed that the same has been in operation for some time, and that the boiler A contains wood which has 70 been treated with liquid already employed twice, and that the boiler B has been filled with fresh wood. From this point the apparatus is operated as follows: The cocks 6 9 10 are opened and the cocks 15, 16, 13, 14, and 5 75 are all closed. The fresh liquid is now forced from the tank C, through the pipes 1 and 2, into the boiler A, displacing the twice-used liquid in the boiler A and forcing it over by way of the pipes 7 4 8 into the boiler B. 80 After the boiler A has been filled with fresh liquid, as described, the cock 6 is closed, the cock 16 is opened, and steam, being turned into the pipe 4, enters the boilers A and B through pipes 7 and 8, and the necessary boiling of the 85 contents is thereby effected. After the boiling has been completed in boiler B, the cock 16 is closed, the cocks 14 and 15 are opened, and the sulphurous acid and steam are blown off 90 through the pipes 12 and 4 to the conduit c, or conveyed off to a suitable regaining apparatus. Meanwhile the liquid contents of the boiler B are drawn off through pipe 18, and the boiler now contains only the partly-disintegrated wood. The liquid from boiler A is 95 now forced into boiler B, (by admitting fresh water to pipe 1 from the tank C,) pursuing the same course as before, and is now liquid

which has been used but once. Boiling is again effected in boiler B, as before. Communication with the various pipes 2, 11, and 7 is now cut off, and the boiler A is emptied and filled with fresh wood. At this point the conditions of the boilers A B are the reverse of what they were at the point where the description of the operation commenced—that is to say, boiler B contains wood which has been treated with liquid already used twice, and boiler A contains fresh wood. Here the operation of the boilers and their connections is as follows: The cocks 6, 15, 16, 13, and 14 are closed, and the cocks 5, 9, and 10 being opened, the fresh liquid is forced into boiler B through the pipes 1 and 3, and the twice-used liquid passes to boiler A by way of pipes 8 4 7. The cock 5 being closed and 16 opened, and steam and sulphurous acid passed into the two boilers A and B through pipes 7 and 8, the boiling operation is continued to the required extent. After the boiling is completed, the cocks 13 and 15 are opened, and 16 being closed, the sulphurous acid and steam are blown off through pipes 11 and 4 and the liquid allowed to pass off through pipe 17.

Having described our invention, we claim—

1. In an apparatus for boiling or digesting paper-pulp, the combination of two similar

boilers, a tank for containing the digesting solution, connected by pipes having suitable cocks to both said boilers, and a pipe for supplying sulphurous acid and steam to the boilers having branch pipes leading into the tops and bottoms of the same, substantially as described. 30 35

2. In an apparatus for boiling or digesting cellulose, the combination of two boilers or digesters, a tank for containing the digesting solution, and a tank for containing fresh water, 40 with a pipe for conveying steam and sulphurous acid to the boilers, both said tanks being connected by suitable pipes with the boilers, substantially as described.

3. In an apparatus for boiling or digesting 45 paper-pulp, the combination of the boilers A B and the solution-tank C with the solution-pipe 1, having branches 2 and 3, leading to the said boilers, and the steam-pipe 4, having the branches 7 8 11 12, also leading to said boilers, 50 substantially as described.

In testimony whereof we have affixed our signatures in presence of two witnesses.

EUGEN BRN. RITTER.
CARL KELLNER.
